UNITED STATES PATENT OFFICE

WILLIAM H. ROBBINS AND RAYMOND F. BOEHLER, JR., OF SPRINGFIELD, OHIO,
ASSIGNORS TO THE WILLIAMS COMPANY, OF LONDON, OHIO, A CORPORATION OF
OHIO

STEEL WOOL MACHINE

Application filed March 24, 1928. Serial No. 264,413.

Our invention relates to steel wool machines.

It is the object of our invention to provide a steel wool machine adapted to employ a single continuous wire which passes through the machine once only, and which is cut down to its minimum size after having passed through the machine, at which time it is cut off in sections. New lengths of wire are supplied to the machine by welding, or otherwise, attaching the new wire to the end of the old wire as it enters the machine.

In particular, it is the object of our invention to provide a machine having a plurality of loops of the single wire, such loops being arranged in groups and each group being spanned by a common cutting tool or group of cutting tools.

It is the object of our invention to provide these loops driven by a single driving sheave, preferably of larger diameter than the oppositely disposed supporting, non-driving sheave.

Heretofore it has been the practice to either provide two idler supporting sheaves of small size, or two synchronized driving sheaves of the same size, but we have found that a material advantage can be secured by driving only one sheave as that eliminates the problem of synchronizing the two sheaves, but more important still, by our invention of a single sheave being driven we can get the application of the power over a broader area with a minimum of bending of the wires by using the larger power-driven sheave and by concentrating the application of the power at one part of the loop of the wire.

We get the further advantage of being able to utilize a plurality of such machines in series, the elevation of the larger sheave being such as to permit the easy conveying of the wire over the machine in which it has been worked upon to the next adjacent machine. It also results in elevating the loops of wire above the machine bed, away from

the neighborhood of the operator, to permit of mechanism being employed, operated and adjusted in a manner not possible when the loops of wire have their sides closely adjacent to the tool bed of the machine.

By our invention we are enabled to employ any number of units, traveling in synchronism with one another, with adequate supply and take-off mechanism to maintain the proper tension.

It is a further object to provide a tool holding mechanism that is so arranged as to give a readily accessible, fine, vertical adjustment of micrometer character, coupled with a lateral adjustment and an angular adjustment for the cutting tools with respect to the wires.

It is a further object to provide in such a combination floating guides for the wires to accommodate the decreasing size of the wire and to always present a flat surface of the wire to the cutting tool in order to insure uniformity of wool.

It will be understood in the steel wool industry that a machine is only successful to the extent that it makes wool of uniform grade and fineness, according to its setting, and this wool should be in continuous strands of appreciable length. In a machine which produces wool not complying with these conditions, the production is purely theoretical and is not successful.

Referring to the drawings:

Figure 1 is a side elevation of the left-hand side of a composite machine.

Figure 2 is a right-hand side of the take-off end of the composite machine.

Figure 3 is a top plan view of one of the machine units.

Figure 4 is a side elevation of one of such units in detail, partially broken away to show the driving gearing.

Figure 5 is a bottom plan view in detail of one section of the machine, showing the looped wires and the overlapping tools.

Figure 6 is a section on the line 6—6 of Figure 4.

Figure 7 is a side elevation of one of the tool supports and adjusting mechanism, 5 partially broken away.

Figure 8 is an enlarged section through one of the floating guides, looped wires and an end elevation of one of the cutting tools engaging said wires.

10 Figure 9 is a top plan view of the arrangement of the wires as they are looped from sheave to sheave.

Figure 10 is a bottom plan view thereof.

15 Figure 11 is a detail side elevation of the take-off and cutting mechanism cutting the wire in sections.

Figure 12 is an end elevation thereof.

18 Figure 13 is an enlarged section of the cut-off mechanism.

20 Figure 14 is a section on the line 14—14 of Figure 7.

Figure 15 is a top plan view of the tool support and tool with the tool supporting arm 59 in section on the line 15—15 of Figure 7.

25 Figure 16 is a section on the line 16—16 of Figure 6 and shows the intermediate rollers and their retaining clips in elevation.

30 Figure 17 is a section on the line 17—17 of Figure 16 and shows the method of attaching the retaining clips to the intermediate rollers.

35 Referring to the drawings in detail, 1 indicates end posts which are joined together at the bottom by horizontal members 2, and at the top by horizontal bed members 3.

40 These posts carry at either end respectively a relatively large driving drum 4 and a relatively small idler drum 5. The lower faces of these drums are in the same plane, such plane being slightly below the bed 3 so that the loops of wire will pass beneath the bed, which loops are looped over the drums 4 and 5.

45 The drum 4 is driven by a power shaft 6, actuated by a pulley 7, a belt 8 and a motor 9. The shaft 6 drives the drum 4 through a worm 10 on the shaft 6 and a worm gear 11 on the drum 4, both of which gears are 50 incased in a casing 12.

As it may be desirable to use a plurality of steel wool units, the driving drum of each unit is connected together by the shaft 6 so that they are driven in synchronism.

55 The supply mechanism consists of a drum of wire 13 carried in a supporting rack 14 with suitable brake mechanism applied to the drum as desired through the brake arm 15 to regulate the speed of the supply drum 13.

60 From this drum passes the wire 16 to the top of the driving drum 4, whence it passes to the idle drum 5, under that drum, under the table 3 in engagement with the cutting tools 17 and thence beneath the driving drum 65 4, over it, and back again to the idle drum

5, making a group of fifteen loops. The exact number may vary, but this is one number of loops that we have found satisfactory because it provides the proper number of loops to span a conventional 2-inch cutting tool 70 17 so that the one tool will bridge the one group of loops of the wire.

The wire then passes laterally, as indicated at 18, from the top of the driving drum 4 to the top of the idle drum 5, where it passes beneath it and performs another group of fifteen loops, which are spanned by the common cutting tools 17. The wire thence passes, as at 19, to the next adjacent driving drum 75 80 of the next adjacent unit.

The wire then continues through any number of such machines until it makes its exit, as at 20, where it passes between the take-off friction rolls 21 and 22, which are geared together by the gears 23 and 24. These gears are driven by the belt 25, actuated by the motor 26. These gears and take-off drums are mounted in spaced frame members 27, which are connected together by the shafts 28 and 29. In these frame members the upper shaft 29 is slidably mounted in the blocks 30 and spring pressed downwardly by the springs 31 in order to accommodate for the inequalities of the size of the wire, and to provide slipping or clutch mechanism so that the pull on the wire may not exceed a predetermined amount.

The wire end 20 thus having been removed from the machine is passed between a similar pair of gear-connected take-off drums, the rollers 32 and 33 geared together by the gears 34 and 35 and supported in uprights 36. The upper roller 32 has a similar spring mechanism 30 and 31 as the upper roller and the other pair of take-off rollers. The four rollers are geared together with respect to the intermediate pinion 37, carried on the frame member 38. The two spaced frame members 38 are connected by horizontal frame members 39 and 40.

The last-mentioned rolls 32 and 33 are provided with a sliding cutting knife 41, which travels along the edge of a cutting block 42 and projects into a slot 43, such block and slot being contained in a lower roller 33. This provides for chopping off the wire in lengths of given size.

Returning to the cutting machine for producing the wool, and particularly to Figures 5 and 6, 7 and 8, it will be noted that the bed 3 of the machine is provided with a pair of spaced arcuate cut-away portions 44, in which rotate semi-circular guide members 45 that are suspended on pins 46 projecting upwardly through enlarged slots 47 in the tool bed 3. These pins 46 are spring suspended by springs 48 from pins 49 on cross members 50, which are in turn supported by the standards 51 mounted on the bed 3 at intervals.

The bottoms of these wire guides 45 are

provided with a plurality of grooves 52 for receiving each wire. The cutting tool 17 is located below these wires and spans the group of fifteen loops of wire guided by each 5 guide member 45. The spring 48 tends to pull this guide upwardly against the intermediate rollers 53, which are interposed between the arcuate cut-away face 44 of the bed and the arcuate semi-circular surface of 10 the floating wire support 45.

The adjustment of the tension on the 15 springs 48 is effected through the nuts 54, which are threaded on the upper ends of the pins 49 and rest upon the upper surface of 15 the plates 50.

In order to support the tool 17 we provide 20 depending laterally, inwardly extending supports of the following character. On the sides of the bed 3 we mount an upwardly extending 20 sleeve 55, which is bolted by the bolts 56 to the sides of the bed 3. Under the edges of this sleeve, which are in the form of flanges 57, we also place shims in order to locate laterally the 25 sleeve in its exact adjustment.

This sleeve is provided with an angular 30 passageway 58 having two faces for receiving a square shaft 59 of the tool holder, the other two square faces of which are received in a complementary angular groove in the side 30 wall of the bed 3.

The upper end of this tool holder 59 is of 35 lesser diameter and threaded as at 60, and has mounted on it a micrometer nut 61, which rests upon the upper side of the sleeve 55 and 35 the bed 3, and is retained beneath an overlapping strap 62 which surrounds the thread 60 at some distance from it and passes to either side thereof, where it has ears 63 which are held by bolts 64 to the upper edge of the bed 3.

40 The rotation of the nut 61 serves to determine the elevation of the tool holder 59, while the square shank of the tool holder fitting in the square groove prevents its rotation.

On the lower end of this tool holder is 45 mounted pivotally a tool holder arm. This pivotal mounting is on the bolt or pivot 65, while the adjustment of this pivotal support is effected by the set screws 66 working in the slot 67, which screws being mounted in 50 the end of the tool holder 59.

The free end of this arm 68 is so arranged 55 that a dove-tail groove 69 is provided so that the tool slide may be adjustably positioned on the arm 68 by the bolt 70 and nut 71.

55 The tool itself is mounted in a groove or slide 72 in the tool slide 73, which is so positioned in the slide 69 by the bolt 70. In this groove 72 is mounted the tool 17 and retained in position by the locating bolt 74.

60 Thus in this tool holder we are enabled to 60 get a vertical adjustment through the nut 61 of very fine character, an angular adjustment through the set screw 66, a lateral adjustment through the bolt 70 as the slot 75 in 65 the arm 68 permits of fore and aft positioning

with respect to the wire of the arm 73 known as the tool slide arm.

We desire to comprehend within our invention such modifications as may be clearly embraced within our claims and the scope of 70 our invention.

Having thus fully described our invention, what we claim is new and desire to secure by Letters Patent, is:

1. In a steel wool machine, a frame having 75 a bed, supporting means for carrying loops of wire passing adjacent the surface of said bed and maintaining them in predetermined position with respect to the cutting means carried by the bed, said supporting means 80 consisting of an arcuate support having a grooved face for engaging with the wires, a pin connected to said support passing through said bed, and yielding means carried on said bed connected to said pin to restrict the lateral movement of the supporting means with respect to the bed.

2. In a steel wool machine, a frame having 85 a bed, supporting means for carrying loops of wire passing adjacent the surface of said bed and maintaining them in predetermined position with respect to the cutting means carried by the bed, said supporting means 90 consisting of an arcuate support having a grooved face for engaging with the wires, a pin connected to said support passing through said bed, and yielding means carried on said bed connected to said pin to restrict the lateral movement of the supporting means within respect to the bed, and anti-friction roller means interposed between said wire supporting means and the bed, said yielding means tending to maintain the anti-friction means in engagement with the wire 95 supporting means and the bed.

3. In a steel wool machine, a bed adapted 100 to have a plurality of wires passing adjacent the faces thereof, a depending and laterally inwardly extending cutting means, holder and cutting means mounted thereon engaging 110 said wires, pressing the said wires towards the bed, a rocking wire support means engaging the other sides of the wires having posit oning grooves in the face thereof oppositely disposed from said cutting means, and yielding means carried by said bed connected to said wire supporting means to limit its rocking on the bed consisting of a pin connected to said wire supporting means passing through said bed freely, and a bracket having 115 a helical spring connected to said pin.

4. In a steel wool machine, a bed adapted 120 to have a plurality of wires passing adjacent the faces thereof, a depending and laterally inwardly extending holder means, cutting means mounted thereon engaging said wires, pressing the said wires towards the bed, a rocking wire support means engaging the other sides of the wires having positioning 125 grooves in the face thereof oppositely dis-

posed from said cutting means, and yielding means carried by said bed connected to said wire support means to limit its rocking on the bed consisting of a pin connected to said wire support means passing through said bed freely, a bracket having a helical spring connected to said pin, and anti-friction means between said wire support means and the bed.

5. In a steel wool machine, a bed adapted 10 to have a plurality of wires passing adjacent the faces thereof, a depending and laterally inwardly extending holder means, cutting means mounted thereon engaging said wires, pressing the said wires towards the bed, a 15 rocking wire support means engaging the other sides of the wires having positioning grooves in the face thereof oppositely disposed from said cutting means, and yielding means carried by said bed connected to said wire support means to limit its rocking on the bed consisting of a pin connected to said wire support means passing through said bed freely, a bracket having a helical spring connected to said pin, anti-friction means 20 between said wire support means and the bed, and adjusting means for adjusting the tension 25 on said spring.

6. In a steel wool machine, a bed adapted 30 to have a plurality of wires passing adjacent the faces thereof, a depending and laterally inwardly extending holder means, cutting means mounted thereon engaging said wires, pressing the said wires towards the bed, a 35 rocking wire support means engaging the other sides of the wires having positioning grooves in the face thereof oppositely disposed from said cutting means, and yielding means carried by said bed connected to said wire support means to limit its rocking on the bed consisting of a pin connected to said wire support means passing through said bed freely, a bracket having a helical spring connected to said pin, anti-friction means 40 between said wire support means and the bed, adjusting means for adjusting the tension 45 on said spring, and means for adjusting the position of the wire cutting means vertically with respect to said wires.

7. In a steel wool machine, a bed adapted 50 to have a plurality of loops of wire supported in parallel relationship with respect to said bed, spaced supporting means between said wires and said bed adapted to rock on said bed, yielding means for limiting said 55 rocking, and cutting means engaging said wires beneath said supporting means whereby the tension on said wires will yieldingly maintain said wires in engagement with said cutting means and said supporting means.

60 8. In a steel wool machine, a bed adapted to have a plurality of loops of wire supported in parallel relationship with respect to said bed, spaced supporting means between said wires and said bed adapted to rock on said bed, yielding means for limiting said rock-

70 ing, cutting means engaging said wires beneath said supporting means whereby the tension on said wires will yieldingly maintain said wires in engagement with said cutting means and supporting means, and means for adjusting the engagement of said cutting means with respect to said wires.

9. In a steel wool machine, a bed adapted 75 to have a plurality of loops of wire supported in parallel relationship with respect to said bed, spaced supporting means between said wires and said bed adapted to rock on said bed, yielding means for limiting said rocking, cutting means engaging said wires beneath said supporting means whereby the tension on said wires will yieldingly maintain 80 said wires in engagement with said cutting means and supporting means, means for adjusting the engagement of said cutting means with respect to said wires, and means for adjusting the rocking of the supporting means on said wires.

10. In a steel wool machine consisting of a 85 plurality of units for having a single continuous wire fed therethrough, means for supplying said wire, means for taking off said wire under tension, means in each unit 90 for supporting said wire in a plurality of loops in each unit, an idler drum for supporting the loops in each unit, a power driven 95 drum for supporting the loops of each unit, cutting means for spanning and engaging each group of loops in each unit, and common means for driving the power driven drums of each unit synchronously, said power driven drums of each unit being of materially larger size than the idler drums whereby the wire when passed from one power driven drum or one unit to another 100 will pass above and clear the idler drum of the adjacent unit.

11. In a steel wool machine, a frame 105 adapted to carry wire, a depending shaft non-rotatably mounted but vertically slide- 110 able in said frame, a micrometer screw, a nut for adjusting the vertical position of said shaft, an arm adjustably and rotatably mounted on the free end of said shaft, means 115 for adjusting the angularity of said arm with respect to said shaft, a tool slide on said arm, and means on said tool slide for adjustably supporting a cutting knife, all of said adjustments being such that said knife may be 120 adjusted inwardly and outwardly with respect to said frame, adjusted angularly with respect to said frame and adjusted longitudinally of said frame.

12. In a steel wool machine, a frame 125 adapted to carry wire, a depending shaft non-rotatably mounted but vertically slide- 130 able in said frame, a micrometer screw, a nut for adjusting the vertical position of said shaft, an arm adjustably and rotatably mounted on the free end of said shaft, means for adjusting the angularity of said arm with

respect to said shaft, a tool slide on said arm, means on said tool slide for adjustably supporting a cutting knife all of said adjustments being such that said knife may be
5 adjusted inwardly and outwardly with respect to said frame, adjusted angularly with respect to said frame and adjusted longitudinally of said frame, adjustable means for adjusting the wear on said
10 micrometer nut, and adjustable means for adjusting the wear on the slide of said shaft.

In testimony whereof, we affix our signatures.

WILLIAM H. ROBBINS.
